UNITED STATES PATENT OFFICE.

WILLIAM F. ENRIGHT, OF ST. PAUL, MINNESOTA, ASSIGNOR TO DOLGEVILLE FELT SHOE COMPANY, OF DOLGEVILLE, NEW YORK, A CORPORATION OF NEW YORK.

DISPLAY CASE.

Application filed July 22, 1925. Serial No. 45,249.

The present invention relates to a sample carrying and display case which is particularly adapted to contain salesmen's samples of footwear.

5 In order to display a group of samples of footwear to a prospective purchaser, a salesman is frequently required, when his samples are packed in an ordinary suit case or similar container, to unpack his samples one by one and lay them out for inspection.

An object of the present invention is to make a combined sample carrier and display case which will retain said samples in a predetermined position, irrespective of the position of the display case when said case is in a closed condition, and to easily and quickly bring any or all of the samples into a display position upon the opening of said case.

20 In order to attain this object, there is provided, in accordance with one feature of the invention, a pair of box like portions connected together by hinged means to permit the closing together thereof, and support 25 rods extending across each of said box like containers, said rods having support means slidably connected thereto with resilient positioning means adjacent each support means to resiliently position said support means 30 upon said cross rods, and straps positioned parallel to the support means to hold the toes of footwear samples, supported on the support means, from displacement.

These and other features of the invention 35 will be more fully brought out in the following description and the accompanying drawings, wherein:

40 Figure 1, is a view in elevation of a display case made in accordance with the present invention with articles of footwear mounted therein, a portion of the case being broken away to show an article of footwear therein; and

45 Figure 2, is an enlarged view in section and elevation, respectively, of a support rod and a hook slidably mounted therein, showing in detail the method of mounting the articles of footwear in the display case.

50 Referring to the drawings in detail, the display case comprises a pair of box like members 1 and 2, hingedly connected at an edge thereof to each other. A handle 3 is provided for carrying purposes, and a lock 4 may also be provided for securing the parts 55 in closed condition.

Extending transversely across each of the box-like portions 1 and 2 are rods 5, which may be of metal, said rods being spaced apart a distance slightly less than the combined length of an article of footwear 9 60 which it is desired to display in said case, and a support means connecting the article to one of said rods. Upon each of the rods 5 are mounted a plurality of support hooks 6 which may be of the type shown in Figure 65 2, each of which is resiliently positioned upon the rod by a pair of rubber washers 7, one of said washers being mounted on either side of each support hook 6. A rod 8 is mounted transversely of each of the box like 70 members 1 and 2 a short distance from what is intended to be the bottom of the case when the case is opened in a display position, as shown in Figure 1. A strap 10 having a buckle 11 therein is positioned laterally adjacent each rod which supports the toes of articles of footwear contained in the case, and these straps may be secured across the toes of the articles of footwear to firmly hold them in position rearwardly of the rods when 80 the case is closed.

The articles of footwear 9 are placed in position within the case and gripped by the hooks 6, which may be positioned upon the rods 5 by manually gripping the washers 7 85 and slidably moving them along the rod so as to bring each article of footwear into a desired position with respect to the other articles of footwear upon the same rod. The rubber washers 7 are of a size to resiliently grip the rod with sufficient force to prevent lateral displacement of an article of 90 footwear carried by its associated hook 6, but also to yield to a reasonable manual pressure applied thereto.

95 The rods 5 are spaced inwardly from the edge of the case a sufficient distance to permit the case to be closed when articles of footwear are positioned with the toes thereof upon the outward side of the rod below the one upon which they are suspended, and in this position the soles of the articles of footwear are resiliently supported by the washers 7 upon the next lower rod. However, when the case is to be closed for a considerable period it is preferable to raise the articles of footwear slightly upward and move the toes thereof into position behind said next lower rod, as shown in dotted lines in Figure 1, so that the toes will be resiliently supported by the washers 7 upon the next lower rod.

iently supported in such position by means of the washers 7 on the next lower rod. The straps 10, mounted transversely of the members 1 and 2 may then be secured across 5 the toe of the articles of footwear to hold them firmly in position.

The support rods serve to support the toes of the shoes in a display position and the straps 10 to retain them in back of the 10 rods when the case is closed, as during shipment.

A further advantage in securing the toes of the shoes in position by means of the straps is found when opening the case in a 15 horizontal position. If the toes of the articles of footwear were not secured in position by the straps, upon opening the case in such horizontal position, the articles would pivot about the rods and hang in a 20 vertical position. When the toes of the articles are secured by the straps, however, they retain their position in the container until the toes are released and moved into a display position. Furthermore, when it 25 is desired to especially display a few of the articles, the strap securing them in position may be released and the toes of these articles may be moved in front of the rods, the rest of the articles being retained in position 30 behind the rods.

What I claim is:

1. A display case, comprising a pair of box-like members hingedly connected together, support rods mounted transversely 35 of each of said box-like members and spaced apart substantially the length of an article

to be supported thereon, manually operable grip means slidably mounted upon each of said rods, and means mounted upon the rod adjacent said grip means to resiliently position said means upon said rod by means of a resilient frictional grip upon the rod. 40

2. A display case, comprising a box-like member having a closure therefor, a plurality of support rods mounted transversely 45 of said box-like member and spaced apart a distance substantially equal to the length of an article to be supported thereon, grip means slidably mounted upon said rods, and means mounted upon said rods adjacent 50 each of said grip means to resiliently position said grip means and to resiliently support a portion of an article carried by a grip means on an adjacent support rod in 55 said case.

3. A display case, comprising a box-like portion, rods mounted transversely of said box-like portion and spaced apart to position a portion of an article to be displayed thereon in overlapping position with a rod next adjacent thereto, article grip means slidably mounted upon said rods, a resilient washer slidably mounted upon said rods upon each side of each of said article grip means to resiliently position said grip means and to resiliently support a portion of an article carried by a grip means on a rod next 60 adjacent thereto, and strap means mounted transversely of the case to retain articles supported on the rods from displacement. 65

In testimony whereof I affix my signature.

WILLIAM F. ENRIGHT.
